UNITED STATES PATENT OFFICE.

HARRY A. DOUGLAS, OF BRONSON, MICHIGAN.

ELECTRICAL CONNECTOR.

Application filed March 13, 1919. Serial No. 282,452.

To all whom it may concern:

Be it known that I, HARRY A. DOUGLAS, citizen of the United States, residing at Bronson, in the county of Branch and State 5 of Michigan, have invented a certain new and useful Improvement in Electrical Connectors, of which the following is a full, clear, concise, and exact description.

My invention relates to circuit continuing devices and has for its general object 10 the provision of a device that serves to include an incandescent lamp or other translating means in circuit with a grounded source of current. The device of my invention desirably includes switching means 15 for bringing the lamp or translating means in and out of circuit.

The invention includes, as a further characteristic, the provision of interengaging formations that serve to limit a coupling shell and a circuit continuing member to one mechanical relation whereby two contacts upon the circuit continuing member may each be individual to another contact 25 within the shell to avoid short circuiting when the shell has a grounded metallic mounting.

The invention is of particular utility in conjunction with automobile lighting circuits, it enabling the employment of standard double pole plugs with single pole incandescent lamps.

I will explain my invention more fully by reference to the accompanying drawings 35 showing the preferred embodiment thereof and in which Fig. 1 is a longitudinal sectional view illustrating a single pole incandescent lamp brought into circuit by the electrical connector of my invention; Fig. 2 40 shows the connector of Fig. 1 adjusted to open the circuit of the lamp, the lamp, however, being omitted to reveal more clearly some of the construction; Fig. 3 is a sectional view on line 3—3 of Fig. 1; Fig. 4 is 45 a perspective view showing some of the parts of Figs. 1 and 2 in separated relation; Fig. 5 is a diagram illustrating the circuit established by means of the connector of the invention; Fig. 6 is a sectional view on line 50 6—6 of Fig. 5 showing, however, entering position of plug; Fig. 7 is a diagram illustrating a circuit established by means of the connector of my invention that is in another association in this figure; Fig. 8 55 is a sectional view on line 8—8 of Fig. 7, showing, however, entering position of plug.

Like parts are indicated by similar characters of reference throughout the different figures.

The metallic cylindrical shell 1 is supported in a holder 2 either to have electrical contact therewith as shown in Fig. 7 or to be insulated therefrom by means of a ring of insulation 3 interposed between the holder 2 and the shell. One of the circuit 60 continuing portions which is adapted to be included in circuit by means of the connector is shown in the form of a single pole incandescent lamp 4 having a contact 5 upon the inner end of its base and connected with one terminal of the filament 6 and a contact 7 upon a side of its base having electrical engagement with the shell 1 and being desirably in the form of a sheath surrounding 70 the lamp base. The end of the shell that receives the lamp base is provided with bayonet slots 8 adapted to receive bayonet pins 9 projecting from the side of the lamp base. The other end of the shell is adapted to receive a plug 10 that constitutes a circuit 80 continuing member and which, like the base of the lamp, is a contact carrier, although the contacts 11 and 12 upon the plug have the axis of the shell disposed therebetween while the contact 5 upon the lamp base is upon or 85 at this axis.

As illustrated in Figs. 5 and 7, one of these contacts (11) is adapted to receive a conductor 13 extending to one pole of the battery 14, the other contact (12) being adapted to receive a conductor 15 that is grounded as to the frame or chassis of the automobile to which the other terminal of the battery or other source of current is also grounded. The end of the shell that receives the plug 10 is provided with bayonet slots 16 each having two seats 17 and 18 (constituting coupling formations) that are separated longitudinally of the shell whereby the bayonet pins 19 (also constituting 90 coupling formations) may be interengaged with the shell at different places longitudinally thereof for the purpose of holding the plug 10 in assembly with the shell while the plug is either in an inner or outer position while assembled with the shell, the arrangement being such that when the plug is in its innermost position it will be included in circuit with the lamp and when it is in its outermost position it will be 100 excluded from such circuit.

A contact carrier is disposed within the

shell, this contact carrier being illustrated in the form of two discs of insulation 20 and 21 which are, by any suitable means, held in fixed relation with the shell. A rearwardly extending spring barrel 22 and a forwardly extending spring barrel 23 are integrally formed as indicated in Fig. 4, these spring barrels being joined by webbing or flanging 24. This webbing or flanging is 10 clamped between said discs. A rearwardly extending spring barrel 25 is held between an insetting ear 26 and the rear disc 20, the flange 27 on this spring barrel being interposed between the parts 26 and 20. The portion 26 is in the form of a ring through which the spring barrel rearwardly extends. The axis of the shell is between the spring barrels 22 and 25 and is coincident with the axis of the spring barrel 23. A coiled spring 20 28 in the spring barrel 22 presses contact 29 rearwardly, this contact projecting through the rear end of said spring barrel. A coiled spring 30 in the spring barrel 25 presses the contact 31 rearwardly, this contact projecting through the spring barrel 25. A coiled spring 32 in the spring barrel 23 presses the contact 33 forwardly, this contact projecting through the spring barrel 23. The inner ends of the contacts 29, 31 and 33 30 are enlarged to limit the extent to which they may be projected from the spring barrels that enclose them. The inner enlargement of the contact 29 is nearer the rear contact end of this contact than the inner enlargement of the contact 31 is to the end of this contact so that when the springs 28 and 30 are free to act to their fullest extent, the contact 29 cannot be projected rearwardly as far as can the contact 31. When the plug 40 10 has its bayonet pins 19 in their forward seats 17 both contacts 11 and 12 respectively engage the contacts 29 and 31. The lamp 4 being in place and the forward contact 5 being co-axial with the shell 1, said lamp 45 is now included in a circuit which contains the conductor 13, the contact 11, the contact 29, the electrically connected and integrally formed spring barrels 22 and 23, the forward contact 33, the contact 5 upon the rear 50 end of the base of the lamp 4, the filament 6 of the lamp, the contact sheath 7 of the lamp base, the metallic shell 1, the ring-like ear extension 26, the spring barrel 25 engaging this extension, the contact 31, the contact 12 and the conductor 15. When it is 55 desired to exclude the lamp from circuit the plug 10 is pressed slightly forward and is turned sufficiently to bring the bayonet pins 19 into alignment with the seats 18, 60 whereafter the springs 28 and 30 are permitted to press the plug rearwardly. Before the bayonet pins 19 reach their seats 18, the inner enlargement upon the contact 29 65 engages the corresponding spring barrel 22 so that the spring 28 is prevented from fol-

lowing the contact 11 during the balance of the rearward movement of the plug 10. The spring 30, however, has no such limitation imposed upon it and therefore maintains the contact 31 in engagement with the contact 12 during the entire rearward movement of the plug 10 and after the engagement of the contact pins 19 with their seats 18. The spring 30 thus holds the plug 10 in its rearmost position in which the contacts 29 and 11 are separated thereby to open the circuit of the lamp, the spring 30 maintaining the parts in this relation until it is desired to again include the lamp in circuit, whereupon the movement of the plug 10 previously described is reversed to bring about the relation shown in Fig. 1. The open circuit position of the plug is shown in Fig. 2, the presence or absence of the lamp desirably having no effect upon the contacts 29 and 31.

The holder 2 that supports the shell 1 may enclose the incandescent lamp. This holder is mounted upon the metallic frame 34 of the automobile by means of a metallic strut 35. If desired, the metallic shell 1 may be insulated from the holder 2 by means of the ring of insulation 3.

In Fig. 7 the shell 1 is shown in direct electrical connection with its holder 2 and in this figure the bayonet pins 19 are on convergent radii so that the plug 10 can only be inserted in the shell 1 when said plug occupies a single definite position with respect to the shell in the initiation of the engagement of the plug and shell whereby the circuit connections illustrated in Fig. 7 are assured whenever the plug 10 is fully inserted. The arrangement of Fig. 7 prevents the short circuiting of the battery by preventing the wrong insertion of the plug.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A connector including a metallic shell having a transverse supporting member disposed therein, a pair of axially disaligned mutually connected and oppositely disposed contacts supported by said member and insulated from the shell, and a third contact clamped between said supporting member and a portion of the shell, said third contact being electrically connected with the shell.

2. A connector including a metallic shell having a pair of axially disaligned mutually connected and oppositely disposed contacts arranged therein and insulated from the shell, a pair of disks bearing respectively against the inner ends of the contacts to pos-

itively position them within the shell, and a third contact electrically connected with the shell and held between one of said disks and a portion of the shell.

- 5 3. A connector including a metallic shell having a pair of axially disaligned mutually connected and oppositely disposed contacts insulated from the shell, a pair of disks arranged transversely within the shell and 10 clamping a portion of said mutually connected contacts between them whereby said contacts are definitely positioned with respect to the shell, and a third contact electrically connected with the shell and having 15 a portion thereof clamped between one of the disks and an inturned portion of the shell.

4. A connector including a metallic shell having a pair of axially disaligned mutually

connected and oppositely disposed contacts 20 arranged therein, a flange common to both of said contacts, a pair of disks fixed within the shell and each having an opening through which the contacts respectively extend, said flange being clamped between said disks 25 whereby the contacts are definitely positioned with respect to the shell, a portion of the shell being inturned and formed into the shape of a ring and a third contact including a flange, said third contact extending through said ring and having its flange 30 clamped between said ring and one of said disks.

In witness whereof, I hereunto subscribe my name this 26 day of February, A. D. 1919.

HARRY A. DOUGLAS.
